Des. 1183

James Meyer, Jr. of New York, N.Y.
Letters Patent No. 1183, Dated June 4, 1860.

The schedule referred to in these Letters Patent and making part of the same.

To all whom it may concern:

Be it known that I, James Meyer, Jr. of the City of New York, County of New York and State of New York, have invented a new and original design for a show card, and I do hereby declare that the following is a full and exact description of the same.

The card has on the top the name of the firm Jules Mumm & Co. as represented in the annexed copy of said show card.

On the left, under the said name of the firm I placed the label of one of the Champagne brands of said firm, bearing the inscription, "Fleur de Sillery. Vin de Dame Jules Mumm & Co. Reims. J. Meyer Jr. New York. Sole Agent for the U.S." an Eagle holding an Anchor in his claws from which a Bell is suspended. - making the ornament.

To the right of the described label is another bearing the inscription: "Vin imperial. Jules Mumm & Co. Reims. J. Meyer Jr. New York. Sole Agent for the United States, an Eagle holding an Anchor in his claws, from which a Bell is suspended, forming the ornament of said label.

Between these two labels is the word Reims, the place where the firm reside, under it is the fac-simile of the signature of the head of the firm Jules Mumm & Co.

On the left, under the first described label is another label highly ornamented, bearing the inscription Jules Mumm & Co. Reims. En Champagne, on each side "Qualite" and "Superieur", under it Verzenay Cabinet & J. Meyer Jr. New York. Sole Agent for the United States.

On the right hand is the fourth label ornamented and bearing the inscription J. Meyer. Jr. New York. Sole agent for the United States, on the left of said label the word, Cabinet, on the right Champagne, in the center a Coat of Arms, surrounded by an oval upon which is written "A plus ultra. from the house of", under it Jules Mumm & Co. Reims.

Des. 1183

Between the third and fourth table just described are placed the mark which is branded on the Boxes, consisting of a Crown with a shield, having a Star J. M. & Co. with an Anchor upon, on both sides of said mark are Corks bearing the brand of the firm Jules Mumm & Co. Reims.

At the bottom of the above described label, marks and names are printed in large letters, J. Meyer, Jr. New York, sole agent for the United States.

The Card is surrounded by a broad Border. What I claim as my invention, and desire to secure by letters Patent, is the combination of the labels of the firm, with the mark of the Boxes, and the Brand of the Cork of the firm Jules Mumm & Co. of Reims, with my name as sole agent of said house, arranged in an artistic as well as in a new and useful manner. . . . . as herein described, and fully represented in the accompanying print.

Witnesses.
